UNITED STATES PATENT OFFICE.

JOHN HORMBY, OF WOONSOCKET, RHODE ISLAND.

STENCIL-CARRIER FOR BUTTON-STENCILING MACHINES.

SPECIFICATION forming part of Letters Patent No. 705,085, dated July 22, 1902.

Application filed April 17, 1902. Serial No. 103,415. (No model.)

To all whom it may concern:

Be it known that I, JOHN HORMBY, a citizen of the United States, residing at Woonsocket, in the county of Providence and State of Rhode Island, have invented certain new and useful Improvements in Stencil-Carriers for Button-Stenciling Machines, of which the following is a specification.

My invention relates to the painting or coloring of buttons by means of pigments or colors applied thereto by means of stencils.

Of even date herewith I have executed an application, Serial No. 103,414, for a patent for the general arrangement and combination of parts of a machine for applying colors or pigments to buttons by means of stencils, upon the frame and general motive mechanism of which many varieties and arrangements of specific mechanisms for executing the subsidiary functions might be used.

It is the object of this invention to provide improved mechanism for manipulating the stencils and buttons and cleansing the stencils, and while the devices and combinations of devices herein described and claimed are adapted for use upon and with the general mechanism described and claimed in my application aforesaid the present mechanisms and combinations are equally well adapted for use for such machines in general, it being only necessary that the general mechanisms act in substantially the same manner.

With the before-mentioned object in view my present invention, generally speaking, consists in the improved combination, arrangement, and construction of parts hereinafter fully described and afterward specifically claimed.

My invention, further and more specifically speaking, may be said to consist in the improved construction and arrangement of the stencil and carrier and their operative mechanism comprising the trip, guide, and cleanser.

In the accompanying drawings, which illustrate this invention, Figure 1 is a top plan view of the machine with the pigment-reservoirs removed. Fig. 2 is a longitudinal vertical sectional view on the plane of lines 2 2 of Figs. 1, 4, and 5. Fig. 3 is a transverse vertical sectional view on the plane of the line 3 3 of Fig. 4 looking toward the left, as indicated

by the arrow. Fig. 4 is a horizontal sectional view on the plane of line 4 4 of Figs. 2 and 3 looking downward. Fig. 5 is a horizontal sectional view on the plane of line 5 5 of Fig. 2 looking downward. Figs. 6 to 13, inclusive, are detail views, of which Fig. 6 is a top plan view, and Fig. 7 a view in side elevation, of a stencil-carrier detached from the machine and having a stencil therein. Fig. 8 shows a trio of stencils and a button stenciled in a combination design thereby. Fig. 9 is a view in elevation of one of the stencil-carrier guides and trippers. Fig. 10 is a view of the means for dropping the stencils in the carriers into a cleansing-bath. Fig. 11 is a sectional view of the air-chamber of the spraying mechanism. Fig. 12 is a fragmentary plan view of the means for oscillating the pigment carrier or reservoir, and Fig. 13 is a vertical sectional view of the sprayer and pigment-reservoir.

Like reference characters indicate the same parts wherever they occur in the several figures of the drawings.

Referring to the drawings by reference characters, A indicates the frame of the machine, which may be made of any appropriate form and any desired material to properly support the various operating parts, cast-iron being usually the preferred material for such structures. In this frame are suitable vertical bearings for four principal shafts *a*, *b*, *c*, and *d*, each of which has a suitable ball step-bearing, as shown especially in Fig. 2. These shafts are geared together in a manner to cause them to move in unison, preferably by means of gear-wheels *a'*, *b'*, *c'*, and *d'*, although other suitable means to this end might be used.

B indicates the horizontal main shaft, driven to rotate continuously from any suitable source of power—as, for instance, a belt leading from a driven shaft to a belt-pulley *B'*, Fig. 4—said shaft *B* having suitably secured upon it a cam *C*, by means of which a pawl-lever *D*, pivoted at one end, as at *D'*, to the frame of the machine and provided with a roller at its opposite end bearing upon said cam is caused to oscillate on its pivot, the roller being held yieldingly in contact with the face of the cam by a spring *D''*, secured to the frame. Pivoted to the lever *D* is a

pawl D³, which engages a ratchet-wheel D⁴ on the shaft a, and during the oscillation of lever D imparts an intermittent rotation to said shaft a and through the medium of gear-wheels a' b' c' d' to the shafts b, c, and d also. a², b², c², and d² indicate similar notched disks secured, respectively, to the shafts a, b, c, and d, a³, b³, c³, and d³ being locking-levers pivoted on eccentric studs adjustably mounted in the frame and carrying rollers a⁴, b⁴, c⁴, and d⁴, adapted to engage in the locking-notches of said disks and normally but yieldingly held against the disks by springs a⁵ b⁵ c⁵ d⁵, said springs connecting the free ends of said levers to a bar E, passing freely through a swiveled block b⁶ upon the free end of lever b³ and pivotally connected at its end to the pawl-lever D. The eccentric pivots of the levers permit of their exact adjustment with relation to the notches in the disks.

F indicates an elbow-handle lever pivoted to the frame, suitably held and limited in its movement by a spring-latch F' and pins F² F³, secured in the frame. This lever F has pivoted to one of its arms a rod F⁴, which passes loosely through a block F⁵, swiveled in the pawl D³, said block being between springs F⁶ on said rod, whereby the pawl is yieldingly held on the rod and may be engaged with or disengaged from the ratchet-wheel D⁴, whereby the intermittent rotation of the shafts a, b, c, and d may be controlled by manipulating the hand-lever F without stopping the main shaft B of the machine. By the means described the shafts a, b, c, and d are given an intermittent rotation, and the momentum is minimized by a friction-strap G, encircling a brake-wheel G' on the shaft a and secured to a bracket G² on the frame.

H indicates the button-carrier, in the form of a disk of sheet metal, secured by screws or otherwise upon a hub H', mounted upon the shaft a above the upper plate A' of the frame A. The disk is provided near its periphery with regularly-spaced button seats or openings, as at H, slotted out to the periphery, and that portion of the disk which contains these button-seats rests upon a brass ring i, resting upon an annular flange or rest I, rising from plate A', (see Fig. 2,) said ring and annular rest being omitted in part immediately underneath a point, as at h² in Fig. 1, to permit the buttons to automatically drop out of their seats after they have been colored into any suitable chute or other receptacle.

J, K, and L indicate the hubs of the stencil-carriers, secured, respectively, upon shafts b, c, and d and provided with radial peripheral openings, regularly spaced and in number and position corresponding with the button-seats in the button-carrier. Into each of these radial openings is secured a plug, as at J' K' L', in the outer end of each of which is pivoted on a horizontal pin an arm, as at J² K² L², and best shown in Figs. 2, 6, and 7. To each of said arms is secured, as by a screw i², a spring i³, which is seated in a groove in

the bottom of the arm, as at K², Fig. 7. A thin sheet-metal arm, which extends beyond the end of the arm to which it is attached and ends in circular or disk forms, as at K³ K³ L³, each such disk being a holder of a stencil-plate of much thinner metal soldered thereto, as at J⁴ K⁴ L⁴, Figs. 6, 7, and 8, the holder being centrally cut away to expose the stencil-plate, said thin sheet-metal arm being provided with an opening to fit over a pin i⁴ and is slipped into position in the groove in arm K² and held therein by spring i⁵ in a manner to permit of its ready removal when desired to change it for a holder for stencil-plates for different sizes of buttons, the several stencil-plates being slotted or cut to form a suitable single design or combination design, according as one or more sets are used, it being understood that there may be only one or any number of stencil-carriers and that the design may be colored on the button by the use of a single carrier or any series of carriers, the number of series depending upon the combination design to be made. These stencil-carriers are so placed with relation to the button-carrier that in their intermittent rotation with their shafts a holder of each stencil-carrier when at rest will be immediately above a button-seat (see Figs. 1 and 2) and below a pigment-supply, as hereinafter described. As the stencil-holders rotate they rest upon suitably-arranged bars, as at j, k, and l, during the whole of their rotatory movement, these bars being curved downward and again upward for a portion of their extent, beginning at the points where the holders move off the button-carrier to permit the holders to drop by gravity into and pass through suitable cleaning solutions contained in tanks j' k' l'. After the holders are lifted out of the solutions they pass along over these bars j' k' l', (see Figs. 1 and 9,) which hold them well above the level of the button-carrier until they reach their positions of rest over the button-seats, when they drop into notches, as at j³, Fig. 9, with the stencil very close above the button in the carrier. The notches j³ at their exit edges are beveled off, as at k³, Fig. 9, and this assists the rise of the holders out of the notches; but the raising is principally effected by pins, as at l³, Fig. 7, in arms J² K² L², which at this moment pass over rollers j⁴, journaled in the upper ends of fixed pillars K⁴, Figs. 2 and 9. After the holders are raised out of the baths they pass over hot-air sprays or jets, as at k⁶ in Fig. 10, and are quickly dried, these jets being supplied with hot air under pressure from any suitable source through pipes j² k² l². The bath is boiling when the stencil passes through.

Loosely journaled on shaft a above the button-carrier is the carrier M, for as many reservoirs of liquid pigment or color as there are series of stencil-holders, one of such reservoirs being indicated at M', Fig. 13, and said reservoirs being removably held in clamps m n o of the carrier M by suitable

clamp-screws, Fig. 1. These pigment-reservoirs do not rotate with the button-carriers and stencil-carriers; but each reservoir contains a pigment or other liquid for use with 5 a particular series of stencils and is maintained practically in position over the button when covered by a stencil of that series. It is desirable, however, that the pigment-reservoirs shall not be over the buttons when 10 the stencils are in position thereon, and provision is made for oscillating the pigment-carrier slightly forward when the stencils are taking their working positions and back again to pass the reservoirs over the stencils 15 while in such position by mechanism now to be described.

P, Figs. 1, 4, and 12, indicates a vertical rock-shaft suitably journaled in the frame of the machine and having a radial arm P', 20 consisting of two parts hinged together for facilitating a change of button-carriers, secured at its upper end and provided with a slot P², embracing a pin P³, secured to the pigment-carrier. At its lower end the shaft 25 P carries another radial arm p, Figs. 4 and 12, which is provided at its outer end with a pivoted latch p', actuated by a spring p² to normally throw its outer end downward into position to cause it to engage over a catch-block p³, secured on the under side of pawl-lever D. When the pawl-lever is actuating 30 the several carriers, as before described, it carries the latch p' and arm p with it and rocks the shaft p a short distance forward, thus causing arm P' to move the pigment-carrier in the same direction and carry each 35 pigment-reservoir a slight distance beyond its stencil and button. When the button is seated, the latch p' comes in contact with a pin p⁴, secured to the frame, which disengages the latch from catch-block p³ and permits a 40 spring p⁵ to draw arm p back, thus giving a reverse movement to the pigment-carrier and carrying the pigment-reservoirs back over 45 the stencils resting on the buttons. It is during this reverse movement that pigment is sprayed through the stencil-plates, it being desirable that the first matter sprayed should not strike the button, but that the spray be 50 allowed to work slightly, so as to properly atomize the material before reaching its position directly over the button. This reverse movement is governed by a piston in an air-cylinder Q, the piston-rod Q' being pivoted to arm p, the cylinder being secured to 55 the frame to slightly oscillate, and having an adjustable air-escape valve Q². The latch p' may be released by moving handle-lever F when desired, a rod q, pivoted to the handle-lever and held by a spring q' against a pin q², being properly placed for this purpose. 60 When the pigment-reservoirs are passing, during their reverse movements, over the stencils and buttons, a charge of pigment is sprayed upon and through the openings of 65 each stencil and upon its button, as before

described, by a current of air which is allowed to escape so as to be inoperative at all other times. The mechanism for this purpose is best shown in Figs. 3, 11, and 13, in which R 70 indicates an air-chamber into which air is forced by pipe R' from any suitable source of air under pressure. R² is a normally closed spring escape-valve, R³ the plug thereof, which carries a roller R⁴ at its outer end. A 75 flexible pipe S leads from the air-chamber to pipe of each of the pigment-reservoirs, as M, Fig. 13, and as long as valve R² is closed a current of air is caused to pass into the reservoir and a spray of pigment to issue from 80 nozzle T, which in working position is passing over the stencil in position on the button. U, Fig. 3, indicates a circular cam-disk on shaft c, having as many raising-cams u as there are button-seats. The air-chamber R 85 is supported, as by a bracket V, immediately over this cam-disk, and when the nozzle T is in position, passing back over the stencil at rest upon a button, the roller R⁴ is in a notch between two raising-cams u, the valve is 90 closed, and pigment is sprayed from the nozzle. At all other times the roller rests on one of the raising-cams and the valve is open, thus permitting the air to escape from the chamber and cutting off the spray from the 95 nozzle.

All of the parts of the machine are timed to cause the different operations to be performed at the proper times, so that a button fed into the carrier either by hand or by any 100 suitable feeding mechanism will be consecutively stenciled by one stencil of each series, so that, for instance, as shown in Fig. 8, it will be colored in stripes crossing it in one direction, then with stripes of the same or a 105 different color crossing it at angles to those first made, and when desired first striped in another direction with shellac or other varnish by another stencil, finally appearing as shown at W in said figure. 110

As before stated, a single stencil or any number of series of stencils may be used, and by simply changing the stencil-plates in the carriers, any desired design or combination of designs may be stenciled upon the button 115 and different button-carriers used for different-sized buttons.

By the operation of the described mechanism a stencil of every series used is simultaneously in working position over one of the 120 series of buttons in the carrier, and as many buttons are stenciled with one pattern as there are series of stencils used, the spraying from the whole number of pigment-reservoirs being simultaneously done, the stencil resting slightly off the buttons to prevent blurring of previous coloring. After each use of a stencil it is automatically cleaned before it comes into use again, thus keeping the stencils clean and assuring clean-cut work with- 125 clogging or gumming the mechanism. After a button is finished and after a stencil

is cleansed any suitable means might be used to dry either or both if thought desirable or necessary.

Having thus fully described my invention, 5 what I claim as new, and desire to secure by Letters Patent of the United States, is—

1. In a button-stenciling machine, a stencil-carrier comprising a hub and radial arms or stencil-holders hinged thereto in combination with a button-carrier and a guide-bar for supporting the outer ends of the stencil-holders above the button-carrier.

2. In a button-stenciling machine, a stencil-carrier comprising a hub and radial arms or stencil-holders hinged thereto in combination with a button-carrier having button-seats, means for moving the carriers in unison to bring a stencil in a holder above a button in a seat in the carrier, and a guide-bar for supporting the holder above the button-carrier until the holder reaches a position above the button in the seat.

3. In a button-stenciling machine, a stencil-carrier comprising a hub and radial arms or stencil-holders hinged thereto in combination with a button-carrier having button-seats, means for moving the carriers in unison to bring a stencil in a holder above a button in a seat in the carrier, and a guide-bar for supporting the holder above the button-carrier until the holder reaches a position above the button in the seat, said guide-bar being provided with a notch into which the stencil-holder drops when that position is reached.

4. In a button-stenciling machine, a stencil-carrier comprising a hub, and radial arms

or stencil-holders hinged thereto in combination with a button-carrier having button-seats, means for moving the carriers in unison to bring a stencil in a holder above a button in a seat in the carrier, and a guide-bar for supporting the holder above the button-carrier until the holder reaches a position above the button in the seat, said guide-bar being provided with a notch into which the stencil-holder drops when that position is reached, and means for raising the holder out of the notch at the end of its resting period.

5. In a button-stenciling machine, a stencil-carrier comprising a hub and radial arms or stencil-holders hinged thereto in combination with means for rotating the carrier, a guide-bar for supporting the holders during such rotation, said guide-bar being depressed for part of its extent, and a tank for containing liquid through which the stencil-holders travel while passing over the depressed portion of the guide-bar.

6. In a button-stenciling machine a stencil-carrier comprising a hub having radial openings in its periphery, plugs secured in said openings and stencil-holders consisting of metal plates pivoted on horizontal pins in the outer ends of the plugs, said plates being enlarged at their outer ends to support the stencils.

Witness my hand, this 31st day of March, 1902, in the presence of two subscribing witnesses.

JOHN HORMBY.
